UNITED STATES PATENT OFFICE.

FREDERICK M. CONLEE, OF MADISON, WISCONSIN, ASSIGNOR TO NORTHERN ELECTRICAL MANUFACTURING COMPANY, A CORPORATION OF WISCONSIN.

BRUSH-HOLDERS.

No. 852,705.

Specification of Letters Patent.

Patented May 7, 1907.

Application filed September 11, 1906. Serial No. 334,140.

To all whom it may concern:

Be it known that I, FREDERICK M. CONLEE, a citizen of the United States, residing at Madison, county of Dane, State of Wisconsin, have invented certain new and useful Improvements in Brush-Holders, of which the following is a specification.

My invention relates to brush-holder devices for dynamo-electric machines and has for its object to improve the same.

The various features of novelty of my invention will be particularly pointed out in the appended claims, but for a full understanding of my invention reference may be had to the following detailed description taken in connection with the accompanying drawing which illustrates a preferred embodiment.

In said drawing, Figure 1 is a plan view of the brush-holder; Fig. 2 is a section taken on line 2, 2, of Fig. 1; and Fig. 3 is a view similar to Fig. 2, with some of the parts occupying different positions, however.

Reference being had to the drawing, 1 indicates a brush-holder frame of any suitable construction having an opening 2 adapted to receive and guide a brush 3, and provided also with the usual slot 4 adapted to receive fastening means whereby the brush-holder 30 may be adjusted with reference to the commutator.

5 is a follower pivoted at 6 between ears 7 and 8, preferably forming integral parts of the frame. The follower is adapted to rest upon the top of the brush when in operative position, so as to press the brush yieldingly against the commutator. The requisite tension upon the brush is secured by means of a spiral spring 9. This spring, which consists of one or more turns, surrounds the axis about which the follower rotates and has its outer end secured to the brush-holder frame at 10 in any suitable manner, preferably so as to make electrical connection with the frame. The inner end of the spring is connected to the follower intermediate the ends thereof; this connection being conveniently made by means of a pin 11 carried by the follower and about which the end of the 50 spring is bent, as at 12.

Normally the follower is in engagement with the brush and the tension of the spring is exerted thereon to press it against the brush. Upon swinging the follower back-

ward out of engagement with the brush 55 through a considerable angle, a point is reached, as indicated in dotted lines in Fig. 3, at which the spring becomes neutral; and, after this point is passed, the tension of the spring is exerted to hold the follower in its 60 inoperative position. In other words, when the follower is moved in either direction so as to bring the pin 11 past the straight line joining the points 6 and 10, the spring has a tendency to carry the follower farther in the 65 same direction. Therefore, when it is desired to remove the brush, the follower is swung backward past the neutral position, as, for example, to the position shown in full lines in Fig. 3, and is then securely retained 70 out of engagement with the brush through the action of the spring. The follower may be prevented from swinging back farther than to the position indicated in full lines in Fig. 3 in any suitable manner, as, for example, consecutive spirals of the spring may be caused to engage with each other, as at 13, when the follower reaches this position.

The follower may conveniently be made U-shaped and be pivoted at the outer ends of the arms thereof, whereby a housing is formed in the follower within which the spring may be located. In this way a substantial and compact construction is secured.

What I claim as new and desire to secure 85 by Letters Patent of the United States, is:

1. In a brush-holder, a frame having a guide for a brush, a follower pivoted to said frame, and a spiral spring arranged to hold said follower in the brush-engaging position 90 or in a position to clear the brush.

2. In a brush-holder, a frame having a guide for a brush, a follower pivoted to said frame, and a spiral spring connected at its opposite ends to the follower and to the 95 frame respectively and arranged to hold the follower in the brush-engaging position or in a position to clear the brush.

3. In a brush-holder, a frame having a guide for a brush, a follower movably mounted on said frame, and a spiral spring tending to move said follower in one direction when the follower is on one side of a predetermined position and to move the follower in the opposite direction when the follower is on the 105 opposite side of said position.

4. In a brush-holder, a frame having a guide for a brush, a follower pivoted on said

frame, and a spiral spring having one or more coils surrounding the pivotal axis of said follower and having its ends secured respectively to the follower and to the frame at 5 such points that the spring serves to hold the follower in the brush-engaging position or in a position to clear the brush.

5. In a brush-holder, a frame having a guide for a brush, a follower pivoted on said frame, a spiral spring having one or more coils surrounding the pivotal axis of said follower and having its ends secured respectively to the follower and to the frame, the parts being so proportioned that the spring 10 normally holds the follower in brush-engaging position but permits the follower to be swung away from the brush to a position 15 wherein the follower is held clear of the brush by the spring.

6. In a brush-holder, a frame having a 20 guide for a brush, a follower pivoted on said frame, and a spiral spring having its ends connected respectively to the follower and to the frame, said spring being so proportioned and arranged that the follower may be 25 moved against the tension thereof from either direction toward and past a position wherein the points of connection of the spring with the follower and the frame are in a straight line including a point on the pivotal axis of 30 the follower.

In witness whereof, I have hereunto set my hand this 8th day of September, 1906.

FREDERICK M. CONLEE.
